[57] **ABSTRACT**

A fluid to be maintained in liquid phase within a cryostat is cooled by means of an auxiliary refrigeration circuit in which an identical fluid is liquefied by the Joule-Thomson expansion process. The auxiliary circuit is supplied with gaseous fluid at a temperature above its Joule-Thomson inversion temperature. The gaseous fluid which is discharged from the cryostat itself also serves to cool the gaseous fluid supplied to the auxiliary circuit and to cause its temperature to drop below the inversion temperature.

**METHOD FOR REDUCING THE CONSUMPTION
OF A CRYOSTAT AND A DEVICE FOR CARRYING
OUT SAID METHOD**

This invention relates to a method for reducing the consumption of a cryostat in which it is desired to maintain a fluid in its liquid phase and to a device for carrying out said method. The invention finds an application especially in the construction of a liquid helium economizer.

It is well known that the isenthalpic expansion of a gas from a medium at the pressure P_1 to another medium at the pressure $P_2 < P_1$ (across a valve, a porous wall or any other device which is capable of affording resistance to flow) is accompanied by a temperature variation, the magnitude and direction of which are dependent on a coefficient referred-to as the differential coefficient of the Joule-Thomson effect. In the case of a given gas and a given pair of pressures, said coefficient can be either positive, negative or zero according to the temperature. The temperature above which there no longer exists any pair of pressures P_1 and P_2 corresponding to a negative coefficient is referred-to as the Joule-Thomson effect inversion temperature. At a temperature below this inversion temperature, the isenthalpic expansion may be accompanied by cooling of the gas.

The application of the Joule-Thomson effect below the inversion temperature to the liquefaction of gases is common practice. A compressed gas is admitted into a heat exchanger, expands through an impedance and then, as it returns through the heat exchanger, extracts heat from the compressed gas which enters the heat exchanger, with the result that said compressed gas arrives at an even lower temperature than the gas which was previously admitted; after expansion, it again picks up heat from the mass of gas which follows and so on in sequence, with the result that partial or total liquefaction of the gas occurs upon expansion.

Economizers of known types make use of an auxiliary refrigeration circuit in which the gas is liquefied by the Joule-Thomson expansion process. In systems of this type, however, it is necessary to resort to the use of an auxiliary source of liquid with a view to supplying this latter to a heat exchanger which has the intended function of precooling the gas injected into the auxiliary refrigeration circuit in order to cause the temperature to fall below the inversion temperature. The known economizer systems therefore call for a source of liquid, pipes for transferring said liquid between the source and the heat exchangers of the auxiliary refrigeration circuit, and a large number of siphons. The corresponding installation is therefore cumbersome and, in the final analysis, the economy which is achieved is of a very low order and rapidly tends to fall to zero if the power of the installation is not of very high value.

This invention is directed to a method for reducing the consumption of a cryostat and to a device for carrying out said method in which the disadvantages attached to known systems of this type are eliminated.

In precise terms, the present invention relates to a method for reducing the consumption of a cryostat in which a fluid is maintained in its liquid phase and cooled in accordance with said method by means of an auxiliary refrigeration circuit in which an identical fluid is liquefied by the method of isenthalpic expansion or so-called Joule-Thomson expansion process, character-

ized in that said auxiliary refrigeration circuit is fed with gaseous fluid at a temperature which is higher than the Joule-Thomson effect inversion temperature in the case of said fluid and that the gaseous fluid which passes out of the cryostat itself serves to perform a contributory function in cooling said gaseous fluid supplied to the auxiliary refrigeration circuit and to cause the temperature of said gaseous fluid to drop below said inversion temperature.

10 The invention further relates to a device for reducing the consumption of fluid of a cryostat which serves to carry out the method hereinabove defined and comprises a refrigeration circuit of the type employed for liquefaction by Joule-Thomson expansion.

15 In a first alternative embodiment, the economizer is characterized in that it comprises:

a source of gas at a pressure P_1 and at a temperature which is higher than the Joule-Thomson effect inversion temperature of said gas,
a heat exchanger comprising a high-pressure circuit supplied with gas from said source and a low-pressure circuit supplied both with the non-liquefied portion of the gas after expansion and with the vaporized portion of the liquid contained in the cryostat,
a gas expansion unit located at the outlet of said high-pressure circuit, the pressure P_2 of the expanded gas at the outlet of said unit being the pressure which prevails within the cryostat, the liquefied portion of said expanded gas being returned into the liquid contained in said cryostat.

20 the overall size of the assembly consisting of heat exchanger and expansion unit being sufficiently small to permit introduction of said assembly through the neck of said cryostat which is sealed by means of a leak-tight plug through which are passed the two circuits for the circulation of gases at the pressures P_1 and P_2 .

25 In a second alternative embodiment, the economizer is characterized in that it comprises:

a pump-compressor assembly for sucking the gas at a pressure P'_2 which is lower than atmospheric pressure and discharging said gas at a pressure P'_1 which is higher than P'_2 ,

30 a heat-exchanger and expansion-unit assembly comprising successively in the direction of circulation of the fluid:

a. a high-pressure circuit supplied with gas at the pressure P' , by said compressor, in which the gas undergoes a pressure drop ΔP_1 ,

b. a gas expansion unit such that the gas on the upstream side of said unit is at the pressure $P_1 = P'_1 - \Delta P_1$ and the gas on the downstream side of said unit is at the pressure $P_2 < P_1$,

c. a vaporization heat-exchanger in which the portion of the gas which has liquefied after passing through the expansion unit is vaporized at the pressure P_2 while cooling the liquid of the cryostat and/or while condensing the vapors of the liquid of the cryostat,

d. a condensation heat-exchanger through which circulates the gas discharged from the vaporization heat-exchanger, said gas being heated while condensing the vapors of the liquid of the cryostat,

e. a low-pressure circuit through which passes the gas discharged from said condensation heat-exchanger, said low-pressure circuit being in

close thermal contact with said high-pressure circuit so as to constitute a main heat exchanger, said gas being subjected to a pressure drop ΔP_2 within said low-pressure circuit which delivers a gas to the pump-compressor assembly at the pressure $P'_2 = P_2 - \Delta P_2$.

f. a circuit for the flow of the vaporized portion of the liquid contained in said cryostat and at the pressure P_3 in close thermal coupling with said high-pressure and low-pressure circuits, said vaporized portion being subjected within said circuit to a pressure drop ΔP_3 so as to be discharged at the pressure $P_3 - \Delta P_3$ which is equal in particular to atmospheric pressure.

the overall size of said heat-exchanger and expansion-unit assembly being sufficiently small to permit of introduction of said assembly into the neck of said cryostat and this latter being closed by means of a leak-tight plug through which are passed the three circuits for the circulation of gases at the pressures $P_1 + \Delta P_1$, $P_2 - \Delta P_2$, $P_3 - \Delta P_3$.

The expansion units employed can be either a capillary tube, an expansion valve, a porous medium, a throttle valve, or any other means of creating a back-pressure by producing expansion as a result of a throttling or wiredrawing effect.

These two alternative embodiments permit a number of different modes of execution, depending on the values of the high pressure P_1 , of the low pressure P_2 and of the pressure P_3 of the main bath of the cryostat.

By way of example and in the case of a liquid helium economizer, it is possible to have,

a. in the first alternative embodiment:

$$P_1 = 3 \text{ to } 20 \text{ atmospheres}$$

$$P_2 = \text{atmospheric pressure} + \Delta P_2$$

$$P_3 = P_2$$

$$\Delta P_1 = \Delta P_2$$

$$= 0.01 \text{ to } 0.1 \text{ atmosphere.}$$

b. in the second alternative embodiment:

$$P_1 = 3 \text{ to } 20 \text{ atmospheres}$$

$$P_2 = 0.05 \text{ to } 0.2 \text{ atmosphere}$$

$$P_3 = \text{atmospheric pressure} + \Delta P_3$$

$$\Delta P_{1,2,3} = 0.01 \text{ to } 0.1 \text{ atmosphere.}$$

But it is also possible to have:

$$P_1 = 3 \text{ to } 20 \text{ atmospheres}$$

$$P_2 = 0.02 \text{ to } 0.05 \text{ atmosphere}$$

$$P_3 = P_2 \text{ (first alternative embodiment)}$$

which would be the case in particular of a cryostat employed below the temperature of the point λ of helium ($T_\lambda = 2^{\circ}17$ K and $P_\lambda = 0.05$ atmosphere), or which would be the case of a cryostat in which the bath of ordinary helium serves to condense the isotope-3 of helium of a separate circuit for cooling at a lower temperature (a circuit for pure helium-3 or a circuit for helium-3 of a dilution refrigerator).

In accordance with another mode of execution of the first alternative embodiment, a part of the gas can be directed towards a compressor or a pump-compressor assembly constituting the source of gas at the pressure P_1 . Similarly, in a particular mode of execution of the second alternative embodiment, the pump can be independent and the gas at the pressure P_1 can be supplied from a source other than a compressor.

The characteristic features and advantages of the invention will in any case become more readily apparent from the following description of examples of construction which are given by way of explanation and not in

any sense by way of limitation, reference being made to the accompanying drawings, wherein:

FIG. 1 is a diagram of the device of the invention in accordance with the first alternative embodiment;

FIG. 2 is a diagram of the device of the invention in accordance with the second alternative embodiment;

FIG. 3 is a simplified diagram of a heat exchanger which can be employed in the first alternative embodiment;

10 FIG. 4 shows a particular form of construction of the economizer in accordance with the second alternative embodiment of the invention;

FIG. 5 shows two details A and B of the economizer of FIG. 4;

15 FIG. 6 shows two further details C and D of the same economizer.

Although the invention can be utilized for a wide range of different gases, the following description refers by way of explanation to a cryostat which contains liquid helium. The inversion temperature of the Joule-Thomson effect in the case of helium is in the vicinity of 50°K. Above this temperature, the helium therefore becomes heated upon expansion. However, this temperature rise is of a very low order since it corresponds to an extremely small difference in specific heat between the gas under pressure and the expanded gas.

20 For example, in the case of helium, the difference in enthalpy at 300°K between the gas at 10 atmospheres and the gas at 0.1 atmosphere is approximately 3 J/g. 25 If the helium injected into the economizer is at a temperature higher than 50°K, for example at ambient temperature, it is therefore apparent that only a few frigories between 50°K and ambient temperature will be necessary in order to liquefy said gas by the cumulative process of Joule-Thomson expansion.

30 In accordance with the invention, the frigories aforesaid are taken from the helium gas which passes out of the cryostat and evaporates at 4°K, for example. The difference in enthalpy of the gas between 4°K and 35 300°K is approximately 1600 J/g. It is therefore necessary to have only a very low gas flow rate in order to cool the gas introduced into the economizer to a sufficient extent to ensure that the Joule-Thomson expansion can produce a cooling action.

40 In FIG. 1, the cryostat 2 of the Dewar vessel type contains liquid helium 4. A refrigeration circuit 8 is introduced into the neck 6 of said cryostat, said circuit being supplied from a source 10 of helium under pressure and at a temperature above the Joule-Thomson effect inversion temperature of helium. The heat exchanger 12 comprises a high-pressure circuit 14 and a low-pressure circuit 16. An expansion unit 18 is located at the extremity of the high-pressure circuit 14. On the downstream side of said expansion unit, the liquefied portion of the expanded helium is returned to the helium contained within the cryostat. The low-pressure circuit 16 is fed with gas both from the non-liquefied portion of the gas after expansion of this latter through the expansion unit 18 and from the vaporized portion of the liquid 4 contained in the cryostat. A plug 20 serves to close the vessel at the top of the neck.

45 If ΔP_1 and ΔP_2 designate the pressure drops within the high-pressure circuit 14 and low-pressure circuit 16, respectively, the source 10 delivers helium at the pressure $P_1 + \Delta P_1$, which is again present on the upstream side of the expansion unit at the pressure P_1 . On the downstream side of said unit the pressure above the

liquid 4 is P_2 and, at the outlet of the low-pressure circuit 16, the helium escapes at the pressure $P_2 - \Delta P_2$ which can be atmospheric pressure.

In FIG. 2, there is shown the device of the invention in accordance with the second alternative embodiment. A pump-compressor assembly 50 draws-up the gas at a pressure $P_2 - \Delta P_2$ and discharges the gas at a pressure $P_1 + \Delta P_1$.

The helium then flows successively through the following units:

a. a high-pressure circuit 52 in which a pressure drop ΔP_1 occurs;

b. an expansion unit 54 in which the helium pressure is P_1 on the upstream side of said unit and P_2 on the downstream side;

c. a vaporization heat-exchanger 56 in which the helium 58 which has been liquefied at the outlet of the expansion unit 54 is vaporized at the pressure P_2 and cools the liquid 60 of the cryostat 62 or, if necessary and depending on the level of the liquid within the cryostat 62, condenses the vapors 64 of the evaporated liquid 60;

d. a condensation heat-exchanger 66 in which that portion of the helium 58 which has vaporized within the heat exchanger 56 is heated from the temperature corresponding to the saturated vapor pressure P_2 up to the ideal condensing vapor temperature corresponding to the pressure P_3 which prevails within the cryostat (and which can be in the vicinity of atmospheric pressure, for example), the temperature rise of said gas being caused by condensation of part of the vapors 64 of the main bath 60 which return to this latter in liquid form;

e. a low-pressure circuit 68 which forms in particular with the high-pressure circuit 52 a heat exchanger 70, the pressure drop within said circuit 68 being ΔP_2 .

The vaporized portion 64 of the evaporated liquid 60 is discharged through a circuit 72 in which there is a pressure drop ΔP_3 , with the result that the pressure of said vapor is caused to change from P_3 to $P_3 - \Delta P_3$; the circuit 72 also forms part of the heat exchanger 70. The neck of the cryostat is closed by means of a plug 74.

Experiments performed by the present Applicant have demonstrated that the helium losses of a cryostat are reduced by more than one order of magnitude when said cryostat is equipped with the device according to the invention. The losses thus reduced are those which are caused by supports placed in a vacuum, by radiation, by the Joule effect in situ, by eddy currents.

One advantageous form of construction of the heat exchanger 12 is illustrated in FIG. 3. In this figure, the heat exchanger is constituted by a hollow cylinder 30 and especially a metallic cylinder surrounding a plurality of tubes 32 which are fed in parallel with expanded gas at the pressure P_2 (arrows 34); these hollow tubes constitute the secondary circuit of the heat exchanger. The primary circuit is constituted by the space formed between the tubes 32 and the cylinder 30. This circuit is associated with an inlet 36 for the admission of gas at the pressure $P_1 + \Delta P_1$ and with an outlet 38 through which the gas is discharged at the pressure P_1 and conveyed to the expansion unit 18.

Since the helium flows in a laminar regime within the tubes 32, it is known that the heat exchange process is not dependent on the diameter of the tubes but on their length (W. H. McAdams, *Transmission of heat*, Chapt. 9.2); these tubes must accordingly have the smallest di-

ameter which is compatible with an acceptable pressure drop.

A calculation which is simplified but has been confirmed by practical experience shows that a tube 30 5 centimeters in length is capable of exchanging the enthalpy corresponding to 2 or 3 milliwatts of refrigeration whilst the corresponding flow rate of helium is approximately 10^{-4} g/s.

Since the pressure drop is proportional to the fourth 10 power of the reciprocal of the diameter it is shown by calculation, for example, that the diameter must be larger than 0.5 mm in order to have a pressure drop ΔP below 0.1 atmosphere with $P_2 = 1$ atmosphere and must be larger than 0.6 mm in order that ΔP should be below 15 0.08 atmosphere with $P_2 = 0.1$ atmosphere.

With a diameter of 0.6 mm, $P_2 = 0.1$ atmosphere, a length of 35 centimeters and a flow rate of 10^{-4} g/s per tube, the present Applicant has observed experimentally a pressure drop ΔP of 0.0025 atmosphere. Taking 20 into account the above-mentioned law, the diameters usually employed will therefore be within the range of 0.5 to 0.7 mm.

So far as the high-pressure circuit is concerned, the 25 problem of pressure drop does not arise and the tubes must be as closely spaced as possible while making allowances for the machining of the centering rings.

There is shown in FIGS. 4 to 6 one particular form 30 of construction of an economizer in accordance with the second alternative embodiment of the invention.

FIG. 4 shows the economizer unit as a whole. The helium is introduced through the high-pressure inlet 100 which communicates with an admission tube 102. The helium passes successively through the main heat exchanger 104, the tube 140, a porous medium 106 which performs the function of expansion unit, the vaporization heat-exchanger 108, the condensation heat-exchanger 110, the tube or closed, hollow shell 112, and is finally discharged through the outlet connection 114. The outlet 116 guides the gas as this latter passes out of the main bath of the cryostat (not shown) which is assumed to surround the vaporization and condensation heat-exchangers 108 and 110; said gas is collected in the annular space formed between the tube 112 and the outer tube or shell 118 which are located within the head of the cryostat.

FIG. 5 shows two details of the device of FIG. 4 as 35 considered at the levels A and B. In FIG. 5A, the high-pressure gas is admitted through the tube 102 at the pressure $P_1 + \Delta P_1$. At the extremity 120, said high-pressure gas spreads out and circulates within the shell 160 between the tubes 122 through which the low-pressure helium circulates in the opposite direction and is discharged at the extremities 124 at the pressure $P_2 - \Delta P_2$. The helium which leaves the main bath of the cryostat flows through a small number of pressure-drop tubes ΔP_3 , only one tube 126 being shown in FIG. 5. Said helium is discharged at the pressure $P_3 - \Delta P_3$ into the chamber formed by the two rings or tube sheets 130 and 132 and escapes through the orifice 134 into the annular space formed between the cylinders 112 and 118.

In FIG. 5B, the high-pressure gas which circulates 40 between the tubes 122 is returned through the tube 140 at the level of the ring or tube sheet 142. The helium which is evaporated from the main bath at the pressure P_3 penetrates into the circuit through the orifice 144, then into the tubes 126. Between the rings 130 and

142, provision is accordingly made for a heat exchanger having three circuits through which gases are circulated at the pressures P_1 , P_2 and P_3 .

In FIG. 5, the references 143 and 145 designate respectively one of the spacer rings or tube sheets and a central rod which is intended to prevent any preferential flow along the axis. 5

FIG. 6 illustrates two details at the levels C and D. In FIG. 6C, the high-pressure gas is admitted through the tube 140. The expanded gas at the pressure P_2 is collected at the extremities 150 of the tubes 122 in the proximity of the ring or tube sheet 152. The so-called condensation heat-exchanger is therefore provided between the rings 142 and 152. The condensed liquid escapes through the orifice 154 and is returned to the main bath. 15

The expansion unit 106 of FIG. 6D is fed with helium at the pressure P_1 through the tube 140. Expansion takes place through three washers 158 of sintered stainless steel. The liquefied portion of the helium is collected at the lower end of the shell 160 which constitutes the so-called vaporization heat-exchanger 108. 20

In this form of construction, the tubes 122, 126, 140 and 160 are advantageously of stainless steel, the thickness of the tube walls being between 0.1 and 0.2 mm. The rings or tube sheets 130, 132, 142 and 152 are of copper and are brazed to the stainless steel tubes. 25

In the form of construction shown in FIGS. 4 to 6, the tubes 122 which constitute the low-pressure circuit have the same cross-section from one end of the heat-exchanger to the other. It is possible in an improved arrangement to make use of smaller tubes in the lower portion of the heat exchanger in which the temperature is at its lowest value since the pressure drop varies approximately as the square of the temperature. In this case, the tubes 122 can have a minimum diameter which is two to three times smaller within said lower portion.

From the foregoing description, it is apparent that the economizer in accordance with the invention has a large number of advantages over known devices of this type: 40

1. it avoids the use of an auxiliary source of liquid helium for the purpose of reducing the temperature of the gas to a value below the inversion temperature, thus simplifying the economizer and increasing its efficiency.

2. it utilizes the property of unbalanced mass flows throughout the heat exchanger and accordingly secures the advantages:

a. of an increasing temperature difference from the cold end to the hot end and this temperature difference in conjunction with the increase in heat conductivity within the highest-temperature zone permits the performance of the greater part of the heat exchange process with a small surface area,

b. of low pressure drops as a result of the low viscosity of the gas within the cold portion which is the largest (90 % of the surface area below 77°K).

3. it does not cause any temperature jump in the gas during cooling since the stream which undergoes a temperature rise is always at the highest possible temperature permitted by the thermodynamic balance, which produces the minimum entropy and consequently permits the maximum efficiency.

4. it makes use of an improved heat exchanger of simple construction which makes it possible:

a. to reduce the pressure losses on the low-pressure side to a minimum value under conditions of equal heat exchange and consequently to choose a low value for P_2 , with the result that the cooling effect can be increased to a very appreciable extent;

b. to ensure maximum heat exchange with the minimum longitudinal conductivity in the metal of the heat exchanger,

c. to have a very high degree of tolerance to impurities by virtue of the large volume left for the gas on the high-pressure side,

d. to prevent "channeling" by virtue of the fact that the greater part of the pressure drops at the hot end which is the most effectively thermalized is localized within each tube,

e. by virtue of the small dimensions of the heat exchanger to introduce this latter into an existing cryostat through the opening which is provided for the filling pipe, for example,

5. it is particularly well-suited to a wide range of possible modes of utilization such as, for example:

a. in the event that the pressure P_2 is atmospheric pressure (the economizer is simplified to the maximum extent),

b. in the event that the pressure P_2 is of the order of 0.1 atmosphere and that a triple-flow heat-exchanger is employed, in which case the maximum efficiency is achieved.

What I claim is:

1. An auxiliary refrigeration unit for reducing the consumption of a fluid existing in liquid and vapor phases within a cryostat, the unit adapted to be connected to a source of high pressure fluid for supply at a temperature which is higher than the Joule-Thomson effect inversion temperature of the fluid, comprising:

a hollow cylinder adapted to be disposed in the cryostat and having an inlet connected to the source of pressurized gas to establish a high pressure flow circuit for the pressurized gas, a gas expansion unit connected to the outlet of said cylinder for expanding said pressurized gas in accordance with the Joule-Thomson effect, the pressure of the expanded gas at the outlet of said unit being at the pressure which prevails within the cryostat, and the liquefied portion of said expanded gas being returned into the liquid contained in said cryostat, and

a plurality of tubes extending through said cylinder and adapted to receive both the nonliquefied portion of said gas after expansion and the vaporized portion of the liquid contained in the cryostat to establish a low pressure flow circuit for said portions and pass said portions in a heat exchange relation to said pressurized gas passing through said cylinder.

2. An auxiliary refrigeration unit for reducing the consumption of a fluid existing in liquid and vapor phases within a cryostat, including a heat exchanger and expansion unit assembly adapted to be connected to a pump-compressor assembly of the type having a gas inlet and a gas outlet for supplying high pressure gas at a temperature above its Joule-Thomson effect inversion temperature, said heat exchanger and expansion unit assembly comprising:

a. a cylindrical shell adapted to be partially immersed in the cryostat liquid;

- b. a plurality of tube sheets, said tube sheets dividing said cylindrical shell into a plurality of chambers including an inlet chamber having means for connection to the outlet of the pump compressor assembly; an outlet chamber having means for connection to the inlet of the pump-compressor assembly; a main heat exchanger chamber; a condensation heat exchanger chamber; and a vaporization heat exchanger chamber; said cylindrical shell having formed therein a plurality of apertures for permitting entry of a portion of the vapor from within the cryostat into said condensation heat exchanger chamber;
  - c. a plurality of longitudinal parallel low pressure circuit tubes connecting said outlet chamber with said vaporization heat exchanger chamber, said low pressure circuit tubes extending through said main heat exchanger chamber and said condensation heat exchanger chamber to divide the space within said main heat exchanger chamber and said condensation heat exchanger chamber into shell sides and tube sides;
  - d. an admission tube connecting said inlet chamber with said main heat exchanger chamber shell side, and a main heat exchanger outlet tube connecting said main heat exchanger chamber shell side with said vaporization heat exchanger chamber and extending through said condensation heat exchanger chamber;
  - e. a gas expansion unit connected to said main heat exchanger outlet tube and being disposed within said vaporization heat exchanger chamber.
- 3. The auxiliary refrigeration unit defined by claim 2 wherein said heat exchanger and expansion unit assembly further comprises:**
- a. an additional pair of longitudinally spaced tube sheets disposed adjacent the inlet end of said main heat exchanger chamber and within said cylindrical shell to define a vapor circuit chamber;
  - b. a jacket mounted on said cylindrical shell for defining a vapor collection space around said cylindrical shell and adjacent said vapor circuit chamber, said jacket having vapor inlet means communicating with the shell side of said vapor circuit chamber and vapor discharge means; and
  - c. a vapor circuit tube connecting said condensation heat exchanger chamber with said vapor circuit chamber and extending through said main heat exchanger chamber.
- 4. The auxiliary refrigeration unit defined by claim 2 further including means mounted within said main heat exchanger chamber for preventing preferential flow of the high pressure fluid through said shell side of said**

10 main heat exchanger chamber.

5. The auxiliary refrigeration unit defined by claim 2 wherein said jacket which defines said vapor collection space comprises a cylindrical housing having a diameter greater than the diameter of said cylindrical shell, said cylindrical housing being mounted concentric with said cylindrical shell and between said vapor circuit chamber and said outlet chamber.

6. A device for reducing the consumption of a cryostat containing a fluid in a liquid phase, comprising:

a hollow cylinder disposed in said cryostat and having an inlet for receiving said fluid in the form of a gas under pressure and at a temperature which is higher than the Joule-Thomson effect inversion temperature of said gas,

a gas expansion unit connected to the outlet of said cylinder for expanding said pressurized gas in accordance with the Joule-Thomson effect, the pressure of the expanded gas at the outlet of said unit being at the pressure which prevails within the cryostat,

a vaporization heat-exchanger disposed in said cryostat and connected to said gas expansion unit for vaporizing that portion of the gas which has liquefied after passing through the expansion unit while cooling the liquid in the cryostat and/or while condensing the vapors of the liquid of said cryostat,

a condensation heat-exchanger disposed in said cryostat and connected to said vaporization heat exchanger for receiving the gas discharged from the vaporization heat-exchanger and the vapors of the liquid of the cryostat, and passing said gas and said vapors in a heat exchange relation to heat said gas and condense said vapors,

a pump-compressor assembly for drawing the heated gas from said condensation heat exchanger and pressurizing said gas, the outlet of said assembly being connected to said inlet of said cylinder, and a first and second series of tubes extending through said cylinder and adapted to receive the gas from said gas expansion unit and the vaporized portion of the liquid contained in the cryostat, respectively, said tubes being adapted to pass said gas and said vaporized portion in a heat exchange relation to said pressurized gas passing through said cylinder.

7. The device of claim 6 wherein a flow circuit connects said condensation heat exchanger to said pump compressor assembly and passes said heated gas in a heat exchange relationship to the pressurized gas passing through said cylinder and to said gas and said vaporized portion passing through said tubes.
